SHOT DRILLING-PELLET IMPACT DRILL BIT

George H. Ramsey, Tulsa, Okla., assignor to Esso Research and Engineering Company, a corporation of Delaware

Application January 29, 1952, Serial No. 268,857

4 Claims. (Cl. 255—61)

This invention concerns a novel method and apparatus for the drilling of bore holes. The invention utilizes what has been called pellet impact drilling in combination with the shot drilling effect. Accordingly, apparatus is provided to eject a high velocity, directed stream of pellets against the central portion of a bore hole. The pellets are directed through a nozzle assembly for this purpose, which is arranged in an enlarged, massive head member having the general configuration of the drilling pattern cut by pellet impacts. The outer portion of this body member is provided with helical grooves. The pellets are circulated after impact so as to seat in these grooves and roll upwardly during rotation of the drill to "shot drill" the walls of the bore hole.

It has recently been discovered that remarkably effective drilling action may be obtained by directing a stream of high velocity pellets against an earth formation to be drilled. By the nature of this process, pellet impact drilling is best adapted for penetrating the central portion of a bore hole to provide a drilled opening of limited diameter. It is the purpose of this invention to improve this basic pellet impact drilling technique by employing therewith an apparatus which is adapted for enlarging the hole diameter normally obtained during pellet impact drilling. At the same time it is the purpose of this invention to provide apparatus which is effective in spacing the jet nozzle used to propel the pellets at an optimum distance from the bottom of the bore hole. It is an additional objective of this invention to provide improved recirculation means for the pellets employed, to facilitate their continuous return and re-entrainment in the fluid jet used to propel the pellets. This is accomplished so as to maintain a high density of the drilling pellets in the drilling zone. The drilling apparatus of this invention is further characterized by providing a gauge size hole of fixed diameter.

The basic principles of pellet impact drilling are fundamentally simple. Means are simply required to provide a jet of high velocity fluid including provision for entraining and accelerating pellets in this jet of fluid. The requisites of this drilling procedure concern the nature of the pellets employed, and the fluid employed therewith as a propelling and recirculation agent for the pellets.

The pellets to be employed must be of substantial size. Thus it has been found that granular pellets or pellets having a diameter less than about $\frac{1}{8}$ of an inch are relatively ineffective in drilling. In general the rate of drilling attainable increases as the size of the pellets is increased. For this reason it is generally preferred to employ the largest pellets possible, consistent with the nozzle size of the apparatus and the fracturing characteristics of the pellets. As will be emphasized, the nature of the drilling fluid employed also has a bearing on the size of the pellets. However, it may be stated that when employing a gas, such as air, for the drilling fluid, pellets of about $\frac{1}{8}$ to a quarter of an inch in diameter are to be employed. When using a liquid, such as water or drilling mud, as the drilling fluid, the pellets may range in size

2

from about $\frac{1}{4}$ to 1 inch. The preferred size range in this case is between about $\frac{1}{2}$ and $\frac{3}{4}$ of an inch.

It is important that the pellets have the greatest practical density. It is apparent that the greater the density of a given sized pellet the greater the kinetic energy which can be attained and the greater the impact force which can be developed. Again, as will be brought out, the separation characteristics of the pellets from the drilling fluid employed play an important part in drilling efficiency. Since the separation rate of the pellets from a fluid depends in part upon the density of the pellets, it is apparent that this factor again dictates use of a high density pellet.

The configuration and surface characteristics of the pellets are also important. The pellets should be substantially spherical in nature and should have a smooth surface so as to limit wear of the jet nozzle assembly through which the pellets are to be ejected. In this connection it is fundamental that a spherical body possesses the best resistance to fracture due to impact; no other shape possesses the mechanical strength of a sphere. The factors of spherical configuration and smooth surface also relate to the separation characteristics of the pellets from the entraining fluid as will be noted below.

In view of these considerations the pellets to be employed are generally metal spheres having the desired properties of impact resistance, hardness, and toughness. Iron, steel and other ferrous alloys may be employed to prepare the pellets. In this connection, however, it should be observed that it is essential that the metal chosen be non-brittle in character. Thus, for example, finished ball bearings have been found to be impractical for use in this invention although ball bearing blanks obtained prior to surface hardening are satisfactory. Due to their high density, tungsten carbide alloys of the less brittle character are attractive for use in the pellets to be employed. Again, alloys of this character or other dense metals may be employed as a pellet core material, surfaced by ferrous alloys having the requisite toughness.

As suggested heretofore, the separation characteristics of the pellets from the drilling fluid play an important part in the efficiency of pellet impact drilling. It is apparent that in jetting a stream of fluid, entraining the pellets referred to, against a formation to be drilled, it becomes important that the pellets readily separate from this stream of fluid. This is required so that the pellets will not be cushioned by the fluid and will not be inefficiently swept from the drilling zone in the fluid flow stream. Again, regardless of the type of pellet recirculation employed, it becomes necessary in some manner to subsequently secure separation of pellets from an upward flow of drilling mud in the bore hole for return and recirculation of the pellets to the drilling zone.

Consequently, as emphasized heretofore, pellets of the character defined must be employed to have the separation characteristics required for effective drilling. In this connection it is apparent that the nature of the drilling fluid employed also affects the separation characteristics of the pellets. From this viewpoint it is desirable to employ a drilling fluid having the lowest viscosity and lowest density practical, consistent with other requirements of the drilling fluid. It has been found that the drilling rate obtainable is proportional to the ratio of the density of the pellets to the density of the drilling fluid. This consideration makes the use of air or other gas attractive. Similarly, if a liquid is to be employed, water or other low density liquid is preferably employed. Nonetheless, if considered desirable, drilling muds of the character conventionally used in rotary drilling may be employed.

Recirculation of the pellets in the immediate vicinity of the drilling zone may be accomplished in a number of ways. When the pellets have been forced against a forma-

tion by jetted fluid, the fluid flow will carry the pellets outwardly and upwardly in an annular channel along the wall of the bore hole. At some point spaced above the bottom of the bore hole, it becomes necessary therefore to separate the entrained pellets from the upflowing drilling fluid. One method by which this may be accomplished is to provide a low velocity fluid zone above the drilling apparatus in which the pellets may settle by gravity into a recirculation system. Such a low velocity zone may be provided by narrowing the cross-sectional area of the apparatus immediately above the drill so as to provide an enlarged annular space in the bore hole. This gravity recirculation can be supplemented or substituted by a mechanical deflection system serving to maintain the pellets in captive recirculation. A shroud may be employed for this purpose of a character substantially blocking the bore hole but containing passages through which drilling fluid and pulverized earth formation may be carried to the surface of the earth.

It is generally desirable in obtaining a suitable ejection of pellets to employ a nozzle assembly utilizing a primary and secondary jet nozzle. The primary nozzle is employed to convert fluid pumping pressure to velocity energy. Consequently, fluid pumped through the primary nozzle is subjected to a substantial pressure drop, of 100 pounds per square inch or more, to provide a constricted directed high velocity jet of fluid. A secondary nozzle is positioned immediately below and concentric with the primary nozzle. The secondary nozzle should have a substantially greater diameter than the primary nozzle to accommodate the total volume of fluid from the primary nozzle in addition to the volume of pellets there entrained. This configuration and arrangement of nozzles, by its nature, creates an aspirating effect which plays a part in the recirculation of the pellets.

Utilizing these basic principles of pellet impact drilling, the present invention supplements this drilling effect by providing means to grind or roll the pellets against the wall of the bore hole during upward recirculation of the pellets from the drilling zone. In the apparatus of this invention, rotation of the drill is employed and this rotation is used as a driving force to propel pellets upwardly from the drilling zone in spiral grooves arranged on a drill head adapted to fit into the bore hole provided by the pellet impact drilling effect.

Two of the basic and preferred forms of apparatus embodying this invention are illustrated in the accompanying drawings, in which:

Figure 1 shows in elevation, partly in cross section, an embodiment of the invention employing a plurality of fluid and pellet ejection nozzles;

Figure 2 is a plan view of Figure 1;

Finally, Figure 3 shows one variation of the invention utilizing a single, centrally positioned, primary nozzle in combination with a single secondary nozzle.

Referring first to Figure 1, a drill is illustrated employing a tubular body member 1 provided with threads 2 which are adapted to permit threaded coupling of this drill to a conventional drill string. The lower termination of the tubular body member 1 is essentially closed but is pierced by cutaway nozzle passages 3. As shown in Figure 2, four nozzle passageways are employed, although if desired a different number of nozzles may be employed. It is the function of nozzles 3 to impose a substantial pressure drop on fluid pumped down through a drill string to and through the nozzles 3. This is operative to convert a substantial portion of the pumping pressure to the form of velocity energy causing ejection of high velocity constricted jets of fluid from the nozzles 3. As illustrated by the arrows in Figure 1, the nozzle passageways 3 are preferably directed inwardly so as to provide a plurality of jetted streams of fluid which are directed downwardly and inwardly toward the axis of the bore hole.

Positioned around the nozzle assembly described is a

drill head 4 having the general configuration shown. The internal portion of the drill head 4 is cup-shaped in nature so that the drilling head may enclose the primary nozzles 3 providing an annular space 5 between the drilling head 4 and the nozzle assembly. This positioning and spacing may be maintained by employing a number of web supports 6 which are fixed to tubular body member 1 and drill head member 4.

The outer surface of the drill head member 4 is also cup-shaped in general configuration. Thus, the maximum diameter of the drill head is at the top thereof, converging downwardly in the curved manner illustrated. This configuration is particularly selected to substantially match the drilling pattern provided by the pellet drilling action at a distance spaced from the bottom of the bore hole.

In the operation of this apparatus, fluid and pellets of the character hereinbefore described are employed. The fluid is pumped through the drill string and through tubular member 1 to be ejected from primary nozzles 3 as jetted streams of high velocity fluid. Pellets following a circulation path along the inside of cup-shaped member 4 are entrained in the fluid jets referred to in the secondary nozzle passageways 7 provided in drill head 4. Here they are entrained in and accelerated by the fluid jets so as to be forcefully propelled against the central portion of the bottom of the bore hole.

The high velocity fluid streams provided cause outward and upward flow of the pellets, after impact, along the wall of the bore hole. This effect causes a certain amount of fluid and solid erosion of the bore hole resulting in a drilling pattern of the character shown. However, as illustrated, in best utilizing jetted fluid energy, the cutting pattern obtained by pellet impacts is relatively narrow in cross-sectional diameter.

Consequently, the enlarged drill head 4, having the shape described, may essentially seat in the bore hole so as to fit on a shoulder portion of the bore hole which is not normally cut away by pellet impacts or pellet recirculation. It will be observed that this results in spacing of the drill head from the bottom of the bore hole so as to maintain a fixed positional displacement of the jets from the bottom of the bore hole. This is a particular feature of this invention since the apparatus by its nature provides an effective means for controlling the distance of the nozzle elements from the bottom of the bore hole so as to secure most effective drilling.

In the upward recirculation path described, the pellets are brought in contact with the spiral grooves 8 on the outer portion of the drill head 4. On rotation of the drill head in the direction indicated, the pellets are trapped in these grooves and are forced upwardly along the grooves by the pressure of the drill head against the wall of the bore hole. This provides what is called "shot drilling" action, resulting in the forceful grinding or rolling of the pellets along the wall of the bore hole. At the same time it will be observed that this action serves to positively propel the pellets upwardly above the drill head for recirculation in the fluid jetting system. Pellets on rolling upwardly in the spiral grooves 8 provided, may roll over the upper lip of the drill head 4 for return into the inner portion of the drill head. Again it is a particular feature of this invention that the pellets rolling over the lip of the drill head in this manner have a relatively low velocity due to the entrainment referred to between the bore hole and the drill head. Consequently, these pellets may readily separate and recirculate to the fluid jets under the action of gravity and the aspiration effect of the nozzles. The pellets are not given an opportunity to be caught in the upward high velocity flow of drilling mud so that at all times the density of pellets in the immediate drilling zone is maintained at a high value.

It is apparent that a number of different nozzle arrangements may be employed in the apparatus described.

As exemplary of this, Figure 3 illustrates a form of the invention utilizing a single pair of centrally directed nozzles. In Fig. 3 a primary nozzle 10 may be fixed to a drill pipe 11 so as to be downwardly directed along the axis of the bore hole. A secondary nozzle 12 may be positioned immediately below and concentric to the primary nozzle 10. Secondary nozzle 12 is cut in a drill head member 4 of the character described in conjunction with Figure 1. Again, the inside portion of member 4 is cut away to provide an annular channel between nozzle element 10 and the drilling head 4 permitting a passageway for recirculation of pellets to the secondary nozzle 12. Support members 13 may extend from the tubular support 11 to the drill head 4 to maintain the fixed positional relationship required. The operation of the apparatus of Figure 3 is essentially that described in connection with Figure 1.

As described, therefore, the present invention employs a massive drill head member within which suitable nozzles are positioned, adapted to jet one or more streams of high velocity pellets against the bottom of a bore hole. Impact of the pellets against the bore hole bottom particularly removes the central portion of the bore hole in a drilling pattern of the nature of a paraboloid of revolution. The drill head referred to is sized and shaped to fit tightly on the shoulders of this drilling pattern so as to normally maintain a fixed displacement of the nozzle openings from the bottom of the bore hole. By arranging spiral grooves on the periphery of the drill head, pellets carried upwardly from the drilling zone are entrapped in these grooves. Rotation of the drill head during operation forces these pellets upwardly along the wall of the bore hole while exerting a shot drilling action. The invention essentially constitutes, therefore, use of a spirally grooved drill head member in combination with a jet nozzle assembly to provide the shot drilling action described.

What is claimed is:

1. The method of drilling a bore hole comprising the steps of: directing a high velocity jet of fluid against the bottom of the bore hole, introducing a plurality of essentially spherical pellets of substantial size into said high velocity fluid jet whereby said pellets are impinged against said borehole bottom, removing said pellets from the bottom of the bore hole by carrying said pellets outwardly and upwardly along the walls of the bore hole in a spiral path while forcing the pellets against the said walls and thereafter reintroducing said pellets into said high velocity fluid jet.

2. Drilling apparatus comprising in combination: a jet nozzle assembly attachable to the lower end of a drill pipe and having at least one jet nozzle adapted to provide a high velocity jet of fluid directed against the bottom of a bore hole, and a drill head member fixed to said nozzle assembly and having an internal cutaway portion defining with said nozzle assembly an annular space adapted to receive pellets of substantial size, said cutaway portion terminating in a bore below and in general alignment with said nozzle assembly, said bore

being essentially smooth and free of obstructions whereby pellets passing thereinto from said annular space will be admixed with and accelerated by said fluid jet and impinged against the bore hole bottom, said drill head member having a generally cup-shaped outer configuration, with its maximum diameter above the bottom of the body and provided with a plurality of upwardly extending helical grooves on its outer surface, said drill head member having an opening, above the region of maximum diameter, of sufficient size to permit entry of pellets into said annular space.

3. Drilling apparatus comprising in combination: a jet nozzle assembly attachable to the lower end of a drill pipe and having at least one jet nozzle adapted to provide a high velocity jet of fluid directed against the bottom of a bore hole, an essentially cup-shaped drill head member supported by said nozzle assembly, said drill head member having its maximum diameter at its upper end and having a central bore whose upper diameter is greater than the outside diameter of said nozzle assembly, said central bore being essentially smooth and free of obstructions, the upper portion of said drill head member surrounding the lower portion of said nozzle assembly and defining therewith an annular space adapted to receive and pass therethrough into said central bore essentially spherical pellets of larger than granular size, the exterior side wall of said drill head member being provided with a plurality of helical grooves extending upwardly to the upper end of said drill head member.

4. An apparatus for drilling a bore hole in the earth comprising a tubular body member attachable to the lower end of a drill pipe, at least one nozzle member attached to the lower end of said tubular body member and adapted to pass fluid from said body member as a downwardly directed high velocity jet, and a drill head member supported by and positioned below said tubular body member, said drill head member having a central bore therethrough positioned in general alignment with said nozzle member, said head member being so positioned with respect to said tubular body member that an annular opening therebetween is provided enabling essentially spherical pellets of substantial size to enter said bore from a region exterior of said head member, said bore being essentially smooth and free of obstructions whereby said pellets will be admixed with and accelerated by said fluid jet and forcefully ejected from the lower end of said bore, said drill head member having a generally cup-shaped outer configuration with its maximum diameter adjacent its upper end and being provided with a plurality of exterior helical grooves extending upwardly to the upper end thereof.
